UNITED STATES PATENT OFFICE.

GUSTAV MORITZ, OF ST. LOUIS, MISSOURI.

EYE-SHIELD FOR SPECTACLES.

SPECIFICATION forming part of Letters Patent No. 730,192, dated June 2, 1903.

Application filed December 18, 1901. Serial No. 86,430. (No model.)

To all whom it may concern:

Be it known that I, GUSTAV MORITZ, a citizen of the United States of America, and a resident of the city of St. Louis and State of Missouri, have invented a certain new and useful Improvement in Eye-Shields for Spectacles, of which the following is a specification.

The object of my invention is to provide a shield for the eyes to protect them from laterally-diverging rays of too strong light or from intense cold, heat, or minute dust particles and which is capable of adjustment on spectacles, so as to be put in place upon them for use or removed at the pleasure or convenience of the user.

Another object I have is to provide a suitable frame, of a strong and light material, that may be covered with a desirable fabric in texture and color to aid in the treatment of weak or squinting eyes.

I further contemplate by the improvement herein to afford means for the air to circulate in the chambers formed by the eye-shields when in place and the spectacle-lens, such chamber being in the form of an ellipse or oval cone spreading inwardly from the lens to the eye-cavities.

With these objects in view my invention consists in certain details of construction, arrangement, and combination of the various parts of the device, as hereinafter set forth, pointed out in the claims, and illustrated in the accompanying drawings, in which—

Figure I is a perspective view of a pair of spectacles carrying the adjustable eye-shield herein mentioned in its place; Fig. II, a similar view of the wire frame or skeleton ready to be covered; Fig. III, a side view of a complete shield detached; Fig. IV, a front view of detached modification in metal or fiber, and Fig. V a side and front view showing the lugs and spring-projection mode of affixing and removing the shield from the spectacle-frame and is the preferred form of frame for my devices.

Referring to the accompanying drawings, the reference-letter A is used to indicate the spectacle-frame and lens complete, to which my eye-shield is adapted, and the numerals 1, 2, 3, 4, and 5 represent the bridge, bow,

lens, temple, and side extensions, respectively, of a pair of spectacles; Figs. III and IV, the complete eye-shield; 8', the inner, and 9' the outer, lugs or fasteners of the shield whereby it is attached to the spectacles.

In the shield-frame, Fig. III, 10 represents the base member, 11' the top member, and 12' the respective end pieces by which the same are formed.

60 6, Fig. I, represents the material or fabric—such as cloth, silk, &c.—used to cover the frame 7, Figs. II and V.

The curved and forked fastening projections 8' 9' are flexible and are adjusted to or removed from the spectacles by the spring in the wire or sheet metal out of which the spring or fastening projections are formed.

The modification shown by Fig. IV is molded from a suitable fiber, such as paper, pulp, asbestos, or the like. The same is also stamped by a die or cut in blanks from thin sheet metal rounded together at the ends, where they are joined either by tonguing or soldering. This form is provided with small holes 12^a for the admission of air.

70 75 Fig. V affords a preferred form for my shield-frame. It is stamped from thin sheet metal—such as brass, tin, or similar material—then rounded to an oval, and fastened together by its ends either by tonguing or soldering. The inner fastening projections 8^b 8^b are similar, in the same material as the frame, and curved inwardly, so as to clutch the lens-frame or lens, as required. The 85 outer fastener 9^b 9^b may be similarly stamped; but I prefer the inverted-U-shaped wire having flaring ends to pass easily over the outer ends of the spectacle lens or bow at the hinges and fastened to the frame.

90 95 In practice if it is desired to employ the all-wire frame, Fig. II, the covering material is cut and fitted thereto, following its configuration, and, thus neatly sewed or fastened, covering the entire frame, the fastener projections excepted. In the sheet-metal form shown in Fig. V the covering material may be glued to the frame after it is joined or may be applied on the straight flat blank before it is joined together. It is apparent that my adjustable shield herein may be made and used on spectacles of every size 100

and description, and but one form is required to fit both spectacle-lenses.

Having thus described my invention, that which I claim as new, and desire to secure by 5 Letters Patent, is—

1. In an eye-shield for spectacles, an open frame and a covering therefor, said frame comprising an upper oval-shaped member, a pair of outwardly-curving parallel side members, and an enlarged, concaved base-forming member, said base member being integral with the side members, substantially as described.

2. In an eye-shield for spectacles, an open frame, a base therefor being inwardly concaved, two parallel side members integral with said base, said side members being curved outwardly and upwardly, an upper open frame secured to said side members 15 above said base, and attaching means for se-

curing said shield to the spectacle-frame, substantially as described.

3. In an eye-shield for spectacles, an open frame, comprising a base and an upper member, said base member being concaved toward said upper member, outwardly-curved side members securing said members together, inwardly-curved, resilient arms extending from the base opposite the side members, said arms extending slightly beyond the upper member, thereby forming attaching means for the eye-shield, a covering for said shield adapted to be secured to the upper and lower member, and held in shape by said resilient arms and side members, substantially as described. 30 35

G. MORITZ.
